[57] CLAIM

The ornamental design for an electrical extension cord, as shown and described.

DESCRIPTION

FIG. 1 is a perspective view of the electrical extension cord showing my new design with the intermediate coil portions being broken away to show indeterminate length;

FIG. 2 is a front elevational view thereof;

FIG. 3 is a left side elevational view of FIG. 2, omitting the right hand connector and cord;

FIG. 4 is a right side elevational view of FIG. 2, omitting the left hand connector and cord;

FIG. 5 is a sectional view taken along lines 5—5 of FIG. 3; and

FIG. 6 is a sectional view taken along lines 6—6 of FIG. 4.
